UNITED STATES PATENT OFFICE.

HAROLD SERRELL, OF NORTH PLAINFIELD, NEW JERSEY; ANNA ELIZA SERRELL AND ARTHUR HAROLD SERRELL EXECUTORS OF SAID HAROLD SERRELL, DECEASED.

COMBINATION-LADDER.

1,096,396.

Specification of Letters Patent.

Patented May 12, 1914.

Application filed October 11, 1912. Serial No. 725,121.

To all whom it may concern:

Be it known that I, HAROLD SERRELL, a citizen of the United States, residing at North Plainfield, in the county of Somerset and

5 State of New Jersey, have invented certain new and useful Improvements in Combination-Ladders, of which the following is a specification.

10 My invention relates to a combination ladder structure. This may be made of small size, adapted for use as a toy, particularly with a toy circus, or it may be made of large size and adapted for the use of artisans and laborers, such as painters, 15 paper hangers or masons, or for the use of gymnasts and acrobats in the performance of tricks, feats of strength and exercises.

The object of my invention is the provision of a combined ladder structure composed of a plurality of units and which are useful as units and which may be assembled in combinations for useful purposes and for amusement.

20 In carrying out my invention, I employ a main ladder member or unit, and one or more auxiliary ladder members or units, by the employment of which the main ladder member or unit may be placed in an inclined position or elevated into a horizontal position, as a platform or scaffold, and the parts are so constructed that an interlocking engagement for connection and support takes place between the main ladder unit and the auxiliary ladder or ladder units. When thus brought together, a firm connection is made which is even augmented by weight placed thereon. The connection and disconnection is made without the employment of other devices and are made 30 with the ladder members or units.

I make the main ladder member or unit narrower than the auxiliary ladder or ladder members, and I project the ends of certain rounds or rungs of the main ladder beyond the parallel sides and I employ clip pieces or hook blocks upon the ends of the sides of the main ladder beyond the projecting rungs. In connecting the parts, the main ladder passes between the sides of the auxiliary ladder or ladders and the clip pieces thereof engage an upper round or rung of the auxiliary ladder, while the sides of the auxiliary ladder bear against the projecting ends of the round of the main ladder and the auxiliary ladder occupies an

obtuse angle to the main ladder. There are also other features of the invention, all of which I will hereinafter more particularly set forth.

In the drawing, Figure 1 is a perspective view illustrating the device of my invention as assembled complete. Fig. 2 is a partial section and elevation at the point of connection of the main and one of the auxiliary ladders. Fig. 3 is an elevation at the upper end of two auxiliary ladders, shown separated in Fig. 1, and which form a pyramidal structure. Fig. 4 is a side elevation illustrating an application of the features of my invention for acrobatic or trick demonstration, in which the main and auxiliary ladders in Fig. 1 are elevated and reversed in the pyramidal structure shown in Fig. 3, and Figs. 5, 6 and 7 are diagrammatic elevations hereinafter described.

The main ladder or unit comprises the sides $a a^1$ and the rounds or rungs between and connecting the same. This main ladder or unit may be made of any desired length or width or weight, according to the uses for which the same is to be employed.

In Fig. 1, I have shown the rounds or rungs in groups, that is the rounds or rungs b , the projecting rounds or rungs b^1 at the ends, and the center rounds or rungs b^2 . I have also shown, at the respective ends of the sides $a a^1$, clip pieces or hook blocks $c c^1$, in close proximity to the rounds or rungs b^1 that have the ends projecting beyond the sides $a a^1$. As shown, these clip pieces or hook blocks are of suitable material, such as cast metal, each with a hollow portion receiving the reduced end of a side and secured thereto by fastening devices, such as rivets, passing through the parts. The lower portions of these clip pieces or hook blocks as hooks are adapted to engage and fit partly around the upper round or rung of one of the auxiliary ladders, or any one of the rungs.

I do not limit my invention to the form of the clip pieces or hook blocks $c c^1$, as they may be made in some other form than that shown, notwithstanding the fact that the form shown is probably the most convenient.

e and f are the auxiliary ladders. They may be of any length or weight of material and in width are preferably slightly wider between the inner faces of the longitudinal members than the over-all width of the

main ladder or unit. They should occupy, with reference to the main ladder, an inclined position as shown. The under surfaces of the parallel members of these auxiliary ladders bear against the projecting ends of the rounds or rungs b^1 , simultaneous with the engagement by the clip pieces or hook blocks of the desired rounds of the auxiliary ladders. This engagement is brought about by placing the auxiliary ladders, with reference to the main ladder, in the opposite inclination to that shown in Fig. 1 with their lower ends nearer together, so as to slip the upper round into engagement with the clip pieces or hook blocks $c c^1$, and then when the auxiliary ladders are moved out at the base into the position shown in Fig. 1, they come into engagement with the projecting ends of the rounds or rungs b^1 and a firm locking contact and engagement is thus formed which is even increased by any weight that is put upon the main ladder or unit.

While I have shown in the drawing the main ladder or unit and the two auxiliary ladders which support the main ladder as a platform in an elevated position, it is quite apparent that if one of these auxiliary ladders were taken away, that one end of the main ladder or unit could rest upon the ground and the main ladder occupy an inclined position supported at the higher end by one auxiliary ladder just the same.

As shown in Fig. 1, all the assembled parts are eminently adapted as a toy for use with a circus outfit, as the same are made and well known in the toy market, and with this form of ladder it will be noticed that the rounds or rungs b^2 at the center of the main ladder are projected considerably beyond the sides $a a^1$ and have connected with them side bars $d d^1$ which form a central widthwise extension to the ladder. In this connection, I have also shown other auxiliary ladders $g h$, each formed with bracket pieces 2 3 secured to the under surfaces of the side members at corresponding ends thereof. These bracket pieces have abutting faces adapted to come together, as shown in Fig. 3, and also in Fig. 4, to bring these ladders $g h$ into inclined or pyramidal form, and therewith I have shown and prefer to employ cap pieces 4 5, sides of which extend over and are secured to similar ends of the sides of one auxiliary ladder, as h in Fig. 1, and the other sides of these cap pieces are adapted to receive similar ends of the other auxiliary ladder, as g , in which case the arrangement shown in Fig. 3 is effected. In this, the meeting faces of the bracket faces 2 3 come together and determine the incline or angle of the ladder with reference to one another, and a locking pin secured by a chain and staple are adapted to pass through 65 the cap piece into the removable section of

the ladders. When separated, these auxiliary ladders $g h$ may be used as shown in Fig. 1. When brought together and secured, they may be used right side up or upside down upon or in connection with the main ladder or unit, or as shown in Fig. 4, the main ladder or unit and the auxiliary ladders $e f$ may be reversed, and by their center round or rung be supported upon the cap pieces 4 5 at the upper ends of the ladders $g h$ in the half round parts of said cap pieces, shown in Figs. 1, 3 and 4, and in this way the main ladder and auxiliary ladders $e f$ become a see-saw for acrobatic or trick performers or in a similar capacity as a toy with circus parts.

As a full size ladder, the device of my invention is very useful for artisans, such as paper hangers, painters, and masons, because a main ladder or unit, short or long, may be employed with auxiliary ladders $e f$, short or long, as a scaffold in their work, it being quite possible in the main ladder to lay boards upon the rounds of the main ladder to complete the platform, and in this connection the ladder may still be used, as shown in Fig. 1, with one or both other auxiliary ladders $g h$ as a means of reaching the level of the platform.

It goes without saying that the length of the auxiliary ladders $e f$ determines the height to which the main ladder or unit is elevated as a platform, and also according to the use desired the main ladder or unit may be made long or short.

It is a fact that painters, paper hangers and masons, in their work, frequently employ two ordinary step-ladders and put a board between them. This is unhandy and the board is of less strength as a support than is frequently desired. In the stairway of a house, it would not be possible to employ two step-ladders with boards between to advantage, but the device of my invention could be used to advantage, because one short auxiliary ladder, as e , could be employed with one long auxiliary ladder as f , and the main ladder or unit be supported thereby, the long ladder reaching to the foot of the stairs and the short ladder upon the landing, as shown in Fig. 5, and in this way the ceiling of the stairway and the side walls thereof can be reached for the work of painter and paper hanger, or one auxiliary ladder could be engaged at any place in its length leaving a part reaching above the main ladder.

Fig. 6 illustrates that in one of the combinations of my improved ladder, that the main ladder or unit short of its prescribed ends may be connected with the auxiliary ladders at any desired or convenient portion of their length either in the full line position of these auxiliary ladders or in the dotted position, while Fig. 7 shows the main

ladder or unit supported at an inclination by one auxiliary ladder at one end.

It further goes without saying that in any of the combinations which can be made 5 or erected with the device of my invention, that the auxiliary ladders, either or both, can be utilized by a workman for access to the main ladder or unit as a platform.

I claim as my invention:

- 10 1. A combination ladder comprising a main part having the ends of a rung projecting beyond the side members thereof, an auxiliary part the sides of which are adapted to bear against the projecting ends of the 15 said rung, and means associated with the main part and adapted to engage the auxiliary part so that the said parts are connected by the engagement between the said means and the auxiliary part and the bearing 20 of the auxiliary part against the said projecting ends of the rung of the main part.
2. A combination ladder comprising a main part having the ends of a rung projecting beyond the side members of the main 25 part, hook engaging devices on the said side members of the main part, and an auxiliary part adapted to bear against the projecting ends of the said rung and to be engaged by the said hook engaging devices to support 30 the said main part.
3. A combination ladder comprising a

main part having the ends of a rung adjacent the ends of the main part projecting beyond the side members thereof, hook engaging devices at the ends of the said side 35 members, and an auxiliary part adapted at one end to bear against the projecting ends of the said rung and to be engaged by the said hook engaging devices for supporting the said main part at one end by the auxiliary 40 part.

4. A combination ladder comprising a main part having the ends of a rung adjacent each end of the main part projecting beyond the side members thereof, hook engaging devices at the respective ends of the 45 said side members at both ends of the main part, and two auxiliary parts both adapted at one end to bear upon the respective projecting ends of the said rungs of the main ladder, and simultaneously to be engaged by the 50 said hook engaging devices at the respective ends of the main part for supporting the main part at both ends by the said auxiliary parts.

Signed by me this 7th day of October, 55
1912.

HAROLD SERRELL.
